UNITED STATES PATENT OFFICE.

CHARLES L. RUDIGER, OF OVERBROOK, KANSAS.

FODDER-FORK.

SPECIFICATION forming part of Letters Patent No. 427,271, dated May 6, 1890.

Application filed January 7, 1890. Serial No. 336,154. (No model.)

To all whom it may concern:

Be it known that I, CHARLES L. RUDIGER, of Overbrook, in the county of Osage and State of Kansas, have invented a new and Improved 5 Fodder-Fork, of which the following is a full, clear, and exact description.

The object of my invention is to provide a simple and convenient implement, whereby 10 corn-fodder or grain in sheaves may be gripped and lifted upon a wagon-bed or other elevated 15 place of deposit, and be instantly released at the will of the operator.

To this end my invention consists in the construction and combination of parts, as herein- 20 after described, and indicated in the claims.

Reference is to be had to the accompanying drawings, forming a part of this specification, in which similar letters and numerals of refer- 25 ence indicate corresponding parts in all the figures.

Figure 1 is a side elevation of the device. Fig. 2 is a view in elevation of the implement, taken in the direction indicated by an arrow in Fig. 1, showing the fodder-clamping fork as 25 it appears when viewed edgewise. Fig. 3 is a plan in section taken on the line 3 3 in Fig. 2, and Fig. 4 is a detached view of a modified form for the keeper-bar of the device.

A represents the handle of the implement. 30 It is made of suitable wood, cylindrical, of convenient diameter to be gripped, and of proper length for its use.

There is a single tine or bow A' formed on or secured to the upper end of the implement. 35 Preferably said bow is bent from the material composing the handle and integral therewith. The bow A' is tapered toward its free end A² for insertion of the same into a mass of fodder, and it should be of such size as to receive 40 within it a sheaf of grain of usual size, or a bundle of fodder loose or tied.

To hold the material it is desired to lift within the embrace of the fork-bow, a metallic keeper-bar B is provided. This is made 45 of a rod of steel or iron, sufficient in length to permit a ring-eye a to be formed integrally thereon near its center of length and afford two limbs 1 2, that extend oppositely at an obtuse angle. On the limb 2 ears a' are integrally produced, which are laterally perforated

and pivotally secured to a similarly-perforated ear on a ring traveler a², that slides freely on the handle A. The limbs 1 2 of the keeper bar B are slightly elastic, and so bent from the point where they are hinged to the ring traveler a² that the upper limb 1 will extend toward the free end A² of the fork-bow A' and have its terminal B' in proximity thereto when the keeper-bar is adjusted to clamp a sheaf or bundle of fodder or other 60 grain-stalks within the bow of the fork. The keeper-bar B may also be made of a flat elastic plate of steel, and have an eye at a³ for the loose connection of the ring traveler a², as shown detached in Fig. 4, whereby a sliding 65 attachment of the bar with the handle A will be afforded. The keeper-bar is furnished with a handle 3 at its lower end for its convenient manipulation.

Upon the handle A a sleeve b is mounted to 70 slide loosely. Said sleeve has two parallel lugs b' formed on its surface near the upper end, between which the lower end of the keeper-bar limb 2 may be located when the sleeve is slid upwardly and suitably adjusted to align 75 the parts. Preferably there is a longitudinal slot b⁴ made in the sleeve b, through which a guide-pin b² is inserted in the handle, and which limits the travel of the sleeve and retains the lugs b' in proper alignment with the 80 end of the keeper-bar B. A handle b³ is projected downwardly and outwardly from the sleeve b for reciprocation of the same when necessary.

In use the material in sufficient quantity to 85 fill the fork-bow A' is placed therein and the keeper-bar B slid upwardly until its limb 1 bears firmly against the fodder or other grain-stalks within the bow. The sleeve b is now moved up, so that the lugs b' will lie on each 90 side of the lower end of limb 2 of the keeper-bar. Said end portion, by reason of the elasticity of the keeper-bar, will bear forcibly upon the sleeve, and thus hold the keeper-bar locked upon the material within the fork-bow. When 95 the bundle of fodder is raised to the proper point for discharge, the handle b³ is pulled upon, so as to slide the sleeve b downwardly, and as the bow portion of the device is turned to bear on some stable point and cause the 100

material held by it to press on the keeper-bar said bar will partially revolve, assuming the position shown in dotted lines in Fig. 1, thus releasing the material, which can be gently deposited at the point desired.

This device is of equal service in transferring fodder from a wagon body or racks to an elevated portion of a barn, where it is to be stored, and greatly expedites the operation, 10 particularly if the fodder has been loaded unbound and has to be removed from the wagon in the same condition.

When the plate-spring keeper-bar shown in Fig. 4 is employed, the hinge-joint at a' in 15 Fig. 1 is dispensed with, as previously indicated, the ring a^2 alone serving to connect the keeper-bar with the handle A. In this case the operation of releasing the keeper-bar requires a longitudinal sliding movement of the 20 same after its lower end has been unlatched from the interlocking contact had with the lugs b' on the sleeve b , said lower end being sprung laterally a short distance to engage the groove between the lugs when it is adjusted 25 to hold a bundle of straw or fodder in the bow A'.

The keeper-bar B, in the preferred form shown in Figs. 1 and 2, as well as the modified form of the same, by its elastic force 30 holds the ring traveler a^2 frictionally engaged with the handle A, which, with the enforced contact of the lower end of the keeper-bar between the lugs b' , prevents slipping of the bar until it is designedly released.

35 Having thus described my invention, what

I claim as new, and desire to secure by Letters Patent, is—

1. A fodder-handling fork having a bowed tine on one end of its handle, a keeper-bar which slides on the handle, and a sleeve which 40 is made to lock the keeper-bar on material placed in the fork-bow, substantially as set forth.

2. The combination, with a handle, a bowed tine thereon adapted to partly embrace grain- 45 stalks or fodder, and a keeper-bar loosely secured to a ring traveler, and thus adapted to slide on the handle, of a sliding sleeve provided with a securing device for the lower end of the keeper-bar, substantially as set forth. 50

3. The combination, with a handle, a bent tine thereon, a ring traveler, and a keeper- 55 bar loosely secured near its middle portion to the ring traveler, of a sleeve that slides on the handle, and lugs on the sleeve which hold the lower end of the keeper-bar aligned on the sleeve, substantially as set forth.

4. The combination, with a rounded handle, a tapering bowed tine formed integral with one end of the handle, a ring traveler, and a 60 slightly-elastic keeper-bar hinged to the ring traveler and adapted to close the opening of the fork-bow, of a cylindrical sleeve placed on the handle and provided with two parallel lugs at its upper end and a handle, substan- 65 tially as set forth.

CHARLES L. RUDIGER.
